DESIGN FOR A BOTTLE

Elizabeth N. Graham, New York, N. Y.

Application August 29, 1945, Serial No. 121,710

Term of patent 14 years

(Cl. D58—5)

To all whom it may concern:

Be it known that I, Elizabeth N. Graham, a citizen of the United States of America, residing in New York city, county of New York, and State of New York, have invented a new, original, and ornamental Design for a Bottle, of which the following is a specification, reference being had to the accompanying drawing, forming part thereof, wherein

Figure 1 is a front elevational view of a bottle showing my new design.

Figure 2 is a right side elevational view. Figure 3 is a left side elevational view, and Figure 4 is a bottom plan view of the bottle shown in Figures 1, 2, and 3.

The rear of the bottle is identical in appearance to the front, except that the faces are in reverse position.

I claim:

The ornamental design for a bottle, substantially as shown and described.

ELIZABETH N. GRAHAM.
